DRIVING MECHANISM FOR EXTENSIBLE
ANTENNAS AND THE LIKE

Emil Carlson, Detroit, Mich., assignor, by mesne assignments, to H. Y. Bassett, O. D. Marcks, and V. D. Hanna, Detroit, Mich.

Application January 26, 1949, Serial No. 72,844

2 Claims. (CL. 250—33)

1

The present invention relates to means for longitudinally actuating extensible and retractable radio aerials of the rod-like self-supporting telescopic type frequently used upon motor vehicles.

The principal object of the present invention is to provide improved actuating means controllable from a remote point for extending and retracting all of the sections of a multi-sectioned telescopic aerial of the indicated type.

Another object of this invention is to provide antenna driving means of the indicated character adapted to employ a conventional electric motor as the source of power, parts being so arranged that the motor may effectively drive the aerial sections through transmission means including speed reduction gearing, but neither the gearing nor the motor being drivable in response to manual actuation of the antenna sections. Thus although the aerial may be raised and lowered by the power means, the power means is completely released from the aerial except during actual driving of the aerial by the motor, and none of the parts can be injured by manual effort exerted upon the aerial itself.

A related object is to provide such improved driving means of a simple, compact and rugged character and which incorporates friction clutch mechanism adapted to prevent injury of the parts in event an attempt is made to drive the aerial beyond the intended limits of its movement, and which also incorporates automatic releasing means of the character previously indicated whereby the driving parts and gearing are disconnected from the antenna except when the motor is energized whereby the antenna is freely movable by hand when desired.

Other objects and advantages of the invention will become apparent upon consideration of the present disclosure in its entirety.

In the drawing:

Figure 1 is a somewhat diagrammatic side elevational view of the front portion of a closed motor vehicle equipped with a radio aerial construction in accordance with the present invention;

Figure 2 is a composite view partly in side elevation and partly comprising a section taken substantially on the line 2—2 of Figure 1 and looking in the direction of the arrows, with parts broken away; and

Figure 3 is a sectional detail taken substantially on the line 3—3 of Figure 2 and looking in the direction of the arrows.

Referring now to the drawing, reference char-

acter 10 designates the fender portion of a closed motor vehicle body generally designated 12. The aerial assembly is intended for installation in the fender or other substantially enclosed body portion in such manner that only the telescopic antenna sections themselves and a very small proportion of the supporting means for the antenna structure project above the supporting fender 10, while when the antenna sections are retracted, they lie within the fender throughout the major proportion of their length. In the illustrated construction, the antenna proper consists of three telescopically interfitting metallic sections 14, 15 and 16 slidably supported by and 15 extensible and retractable with respect to a housing tube 20 supported by and within the fender. The housing tube is supported at both its upper and lower ends by the fender. At its upper end, the housing tube carries a tubular sheet metal neckpiece 22 of reduced diameter which projects upwardly through the fender and the outer end of which is threaded for reception of the domed cap nut 24. The cap nut clamps the neckpiece and thereby the housing assembly to 25 the fender. When tightened, the cap nut bears downwardly against a tubular filler member 25, the lower end of which is shaped to conform to the fender and which bears against a gasketing pad 26 seated against the fender. The housing tube is thereby drawn upwardly against a filler piece 28, which in turn bears against the underside of the fender. The filler piece 28 is formed as a sheet metal cup fitted upon the reduced neck portion 22.

30 The cap nut 24 has an axial opening 30 therethrough which the antenna sections extend, and an insulating bushing 32 and a metallic contact tube 34 are also concentrically fitted in the opening 30 surrounding the antenna assembly.

40 The contact tube 34 is in continuous electrical connection with the antenna elements through the agency of a bowed spring wire contact brush 35 contained in the tube 34 and bearing against the outer antenna section 16. The contact tube 45 34 is fixed in position by the terminal 36 which projects through the side of the housing tube 20 and into electrical connection with the contact tube 34. Terminal 36 is, of course, insulated from the housing tube 20 and is carried by a lead-in cable 38. It will be recognized that the lead-in and connecting parts may be of conventional or any suitable construction.

The insulating sleeve 32 is shown as formed integrally with a filler block 40 fitted into the upper end of the housing tube and neckpiece. A par-

55

titioning disc 42 is fitted and secured in transverse position in the lower end of the housing tube and may also be formed of plastic or other insulating material. A guide tube 44 is supported in fixed axial position within the housing tube by the members 40, 42. The guide tube 44 may also be formed of insulating material and fitted in suitable axial counterbored recesses in block 40 and disc 42, the outer antenna section 16 being slidable therein.

Outward movement of the antenna sections with respect to one another and with respect to the contact tube 34 is restricted by suitable inwardly directed flanges as 45, 46 and 47 formed at the tops of the tubes and which coact with enlarged lower portions formed on the lower extremities of the antenna sections. The enlarged portions formed at the lower ends of the antenna sections 15 and 16 may be formed by swaging as indicated at 48. The enlargement at the lower end of the central antenna rod 14 is formed by a short sleeve 49 secured to the lower end of rod 14 and projecting downwardly a short distance below the rod to form a downwardly opening socket for the reception of the upper end of the actuating wire or band 60, which is suitably reduced, inserted in the socket, and secured therein by crimping the sleeve inwardly.

At its lower extremity, the housing tube 20 is carried by and secured to a casing 50 also formed of sheet metal and the upper extremity of which carries an integral collar 52 fitted into the lower end of the housing tube and secured thereto as by the screw means 54. The casing 50 is of generally rectangular cross section, the bottom of the casing being secured by the bracket 55 attached as by nut and bolt means 56 to the fender 10.

The driving band 60 is flexible but substantially inelastic and may be formed of a suitable strong insulating plastic such as nylon. The band is of rectangular cross section and is secured at its upper end to the inner antenna section 14 in the manner described, and extends slidably downwardly through and outwardly below the bottom of the casing 50, axial openings for free passage of the band therethrough being formed in the disc 42, in the bottom wall of the casing 50, and in the bracket 55.

The portion of the band which projects downwardly below the bracket 55 is slidably fitted in and protected by a guide tube 62 which may be flattened to substantially conform to the band in cross section, and thereby to key the wire against twisting about its longitudinal axis. The tube 62 may be formed of metal and is secured to the bracket and to the bottom of the casing 50 by suitable coupling means such as is generally designated 64. The band is provided along one of its narrower edges with transverse rack teeth 65 which mesh with the corresponding teeth of a gear 66 carried in the casing 50 upon a transverse shaft 68. The gear is loose on the shaft and is provided with a pair of aligning flanges as 72 which project therefrom beyond and on either side of the toothed portion of the gear and which lie beside the band 60 to hold the band against lateral disalignment with respect to the gear. The other narrow edge of the band may be slidably fitted in a guide slot 74 formed in a hollow frame 70 supported in the casing 50. The frame 70 also supports the shaft 68 which is journaled in smooth bearings as 75 therein.

The shaft is drivable by an electric motor 76, only the casing of which is shown, since its de-

tails form no part of my present invention. The motor carries a worm 78 meshing with a worm wheel 80 fast upon the shaft 68 upon one side of the gear 66.

Upon the other side of and spaced from the gear 66, the shaft 68 carries a diametrically projecting driving pin 82 which is loosely engaged in a V-shaped cam notch 84 formed in the adjacent face of a clutch disc 85. Clutch disc 85 is limitedly slideable and also limitedly rotatable on the shaft 68, the sliding movement of the clutch disc being insufficient to permit the notch to move entirely free of the pin, so that the disc is always drivable by the shaft through the pin. The opposed face of the gear 80 serves as a co-acting clutch plate, and a friction disc as 86 is preferably interposed between the gear 66 and clutch plate 85.

The pin and notch portions 82, 84 are so positioned and proportioned that the plate 85 is movable axially along the shaft toward the gear 66 to a position in which it clutches such gear to the shaft when cammed in that direction by the driving pin 82 in response to rotation of the shaft and pin by the motor. When the motor is de-energized and the shaft is stationary, the plate may move away from the gear 66 far enough to free the gear for rotation independently of the shaft. It will be understood that the clutch plate cannot move inwardly toward the gear far enough to free the notch from the pin, and that when the clutch is engaged in the manner described, the gear is clamped between the friction plate 86 and the opposed flat face of the worm wheel 80.

When the motor is energized, the pin tries to climb one of the sloping sides of the notch 84 and cams the clutch plate inwardly until the driving gear 66 is tightly clutched, whereafter, since the pin is still engaged in the notch, the pin drives the plate 85 and thereby frictionally drives the gear 66. The friction between these parts may be so adjusted that when the antenna reaches the limit of its travel, disc 85 may turn with relation to the driving gear 66. Due to the V-shape of the notch, the aerial is drivable in either direction in the manner described, the motor 76 being reversible for this purpose. When the motor is de-energized, if the aerial is moved by hand, the band 60 merely slides longitudinally and turns the gear 66, but since due to the loose engagement between the pin and slot 82, 84, the plate 85 is free to move away from the gear, the gear cannot drive the shaft or the worm wheel and the antenna is freely movable despite the locking effect of the worm-type driving means.

The guide tube 62 may be bent to curved form or any other desired or convenient shape for installation of the same beneath the fender, the shape in which it is shown in Figure 1 being illustrative only.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

What is claimed is:

1. Driving means for an extensible antenna or the like comprising an elongated flexible but substantially inelastic actuating element formed of insulating material mechanically connectible to such an antenna, a rotary driver engaging one face of said element to actuate the same and thereby to actuate an antenna connected to the

actuating element when the driver is rotated, means for rotating the driver including a shaft upon which the driver is loosely mounted, clutch means for coupling the driver to the shaft, keying and camming means for actuating the clutch means and driver, means for connecting a driving motor to the shaft, said keying and camming means including a clutch plate axially slidable on the shaft, and relatively inclined camming abutment portions carried partly by the shaft and partly by said plate whereby when the shaft is turned, the engagement of said portions urges the plate longitudinally toward the driver.

2. Driving means for an extensible antenna or the like comprising a rack adapted to be mechanically connected to but separate and insulated from such an antenna and toothed along one side thereof, a gear meshing with the rack for driving the same, and driving means for the gear including a shaft upon which the gear is loosely mounted, clutch means for coupling the gear to the shaft, driving and camming means for actuating said clutch means to and from engaged relation and for rotating such clutch means and gear, means for connecting a driving motor to the

shaft, another gear fast on said shaft beside said first mentioned loose gear, said driving and camming means including a clutch plate axially slidable on the shaft on the opposite side of the loose gear from the fast gear, and relatively inclined camming abutment portions carried partly by the shaft and partly by the plate whereby when the shaft is turned, the engagement of said portions urges the plate longitudinally toward said gears to clutch the loose gear between the plate and the fast gear.
